UNITED STATES PATENT OFFICE

152,769

DESIGN FOR A THERMOSTATIC CONTROL
GAS VALVE UNIT OR SIMILAR ARTICLE

Michael J. Caparone, Monterey Park, Calif., assignor to Grayson Heat Control, Ltd., Lynwood, Calif., a corporation of California

Application January 27, 1947, Serial No. 136,462

Term of patent 14 years

(Cl. D81—2)

To all whom it may concern:

Be it known that I, Michael J. Caparone, a citizen of the United States, residing at Monterey Park, California, have invented a new, original, and ornamental Design for a Thermostatic Control Gas Valve Unit, or Similar Article, of which the following is a specification, reference being had to the accompanying drawing, forming a part thereof.

In the drawing:

Figure 1 is a front elevational view of a thermostatic control gas valve unit illustrating my new design;

Figure 2 is a side elevational view of the thermostatic control gas valve unit illustrated in Figure 1; and

Figure 3 is a top plan view of the unit shown in Figures 1 and 2.

The dominant features of my design reside in the portions shown in full lines.

I claim:

The ornamental design for a thermostatic control gas valve unit or similar article, as shown and described.

MICHAEL J. CAPARONE.
